HANDLE

Thomas Lamb, New York, N. Y.

Application January 22, 1947, Serial No. 723,500

5 Claims. (Cl. 292-347)

1

This invention relates to handles and pertains particularly to torque handles, i. e. handles by means of which torque or twisting or turning force may be applied to an object by the human hand to turn it around an axis of rotation, or to resist such turning. Common articles to which the principles of the invention may be applied are door knobs, valve handles, faucet knobs or handles, dial knobs or handles, tool handles and the like. Other common articles, not usually referred to as handles, but to which the principles of the invention may also be applied are caps, covers and other closures for bottles, jars, containers and the like where torque is required to open or close the same.

It is an object of the invention to provide a handle which is so constructed, taking into consideration the anatomy of the human hand and its functioning, as to enable the hand to function more efficiently in performing turning or twisting operations. That is, the handle is so constructed as to enable the hand to apply greater torque with the same apparent effort, or the same torque with less apparent effort. Reduction of fatigue and discomfort are also important objectives.

Other objects and advantages of the invention will appear hereinafter.

A preferred embodiment of the invention selected for purposes of illustration is shown in the accompanying drawings, in which,

Figure 1 is a top plan view, and Figures 2 and 3 are front and side elevations, respectively, of a handle embodying the invention.

Figure 4 is a top plan view, and

Figures 5 and 6 are front and side elevations, respectively, of a modified form of handle.

Referring to the drawings, and particularly to Figures 1, 2 and 3, the invention is illustrated as applied to a handle comprising a cylindrical body 1 which is symmetrical with respect to an axis of rotation 2 extending longitudinally therethrough. Preferably the outer end surface 3 of the handle is rounded convexly to seat comfortably in the palm of the hand, and the inner end surface 4 from which the shaft or spindle 5 projects may be flat or otherwise shaped depending on the use to which the handle is to be put.

The outer peripheral surface of the body 1 is provided with an undulating groove 6 extending entirely around the axis of rotation, which said groove, in the embodiment illustrated in Figures 1, 2 and 3 is V-shaped in cross section in order to provide a wedging action on the thumb and fingers as they grasp the handle.

The peaks 7 of the undulating curve formed by the intersection of the upper edge of the groove and the outer periphery of the handle lie tangent to a plane of reference 8, while the

2

troughs 7' of the undulating curve formed by the intersection of the lower edge of the groove and the outer periphery of the handle lie tangent to a spaced plane of reference 8'. Said planes of reference extend through the body 1 in directions perpendicular to the axis of rotation, and the points of tangency of said peaks and troughs with said planes of reference are evenly spaced around said axis of rotation at angles which are even parts of 360°, as in the present case, successive points of tangency are spaced at 90°. If the number of complete undulations is increased from two, as shown, to three, however, the number of points of tangency would be increased to six, which said points would be spaced at angles of 60°. Likewise, if the number of complete undulations is increased to four, there would be eight points of tangency spaced at 45°. The selection of the desired number of complete undulations depends on the size of the handle and the use to which it is to be put. Likewise the use to which the handle is to be put determines the width and depth of the undulating groove as well as the pitch of the undulations, i. e. the steepness of the curves of the undulations as indicated by the distance between the planes of reference 8, 8'. For example, for a valve handle, two complete undulations of fairly steep pitch may be desirable. On the other hand, for a jar cover, three or four complete undulations of shallow pitch may give better results.

The shape of the body 1 may also be varied as desired. Thus, the basic shape of the peripheral surface of the body within which the groove is formed may be not only circular as shown in Figures 1, 2 and 3, but may be elliptical, square or diamond shaped, for example. In cases such as an elliptical or diamond shape, however, in which one transverse dimension, measured at a plane of reference, is longer than the other, I have found it advantageous to shape the body in such manner that, considering the body as divided into two sections by the undulating groove, the longest transverse dimension of each section, measured at its plane of reference, intersects the longest transverse dimension of the other section, measured at its plane of reference, at a right angle.

Thus, referring to Figures 4, 5 and 6, I have illustrated a modified form of handle in which the basic form of the body 11 is elliptical, and in which the elliptical form is again symmetrical with respect to the axis of rotation 12. The peripheral surface of said body is provided with an undulating groove 16 consisting of two complete undulations, said groove being substantially U-shaped and extending entirely around the axis of rotation 12. As before, the peaks 17 and troughs 17' of the undulating curves lie tangent

to spaced planes of reference 18, 18', and successive points of tangency are spaced at 90°.

If it be considered that the handle is divided into two sections by the groove 16, it will be noted that the major axis of the ellipse taken at the plane of reference 18 in the upper section intersects the major axis of the ellipse taken at the plane of reference 18' in the lower section at a right angle.

As before, the outer end surface 13 is rounded convexly and all adjoining and meeting surfaces may be faired into each other to eliminate sharp corners and ridges.

In handles constructed in accordance with the present invention the undulating groove is shaped to receive the thumb and fingers and the undulations provide surfaces against which the thumb and fingers may exert relatively heavy pressure without slipping and without discomfort.

It will be understood that the invention may be variously modified and embodied within the scope of the subjoined claims.

I claim as my invention:

1. A torque handle comprising a body which is symmetrical with respect to an axis of rotation extending longitudinally therethrough, the outer peripheral surface of said body having an undulating groove formed therein extending entirely around said axis of rotation, said groove being of sufficient width and depth to receive the thumb and fingers to provide surfaces which are inclined to the direction of thrust of the thumb and fingers in the turning of the handle and against which the thumb and fingers may exert pressure.

2. A torque handle comprising a body which is symmetrical with respect to an axis of rotation extending longitudinally therethrough, the outer peripheral surface of said body having an undulating groove formed therein extending entirely around said axis of rotation, said groove dividing said body into two sections, each of which is substantially elliptical in transverse cross section, with the major axis of each ellipse intersecting the major axis of the other ellipse at a right angle, said groove being of sufficient width and depth to receive the thumb and fingers to provide surfaces against which the thumb and fingers may exert pressure.

3. A torque handle comprising a body which is symmetrical with respect to an axis of rotation extending longitudinally therethrough, the outer peripheral surface of said body having an undulating groove formed therein extending entirely around said axis of rotation with the peaks of the undulating curve formed by the intersection of the upper edge of the groove with the periphery of the handle and the troughs of the undulating curve formed by the intersection of the lower edge of the groove with the periphery of the handle lying tangent to spaced planes of reference extending through said body in directions perpendicular to said axis of rotation, the points of tangency of said peaks and troughs to said planes of reference being evenly spaced around said axis of rotation at angles which are even parts of 360°, said groove being of sufficient width and depth to receive the thumb and fingers to provide surfaces which are

inclined to the direction of thrust of the thumb and fingers in the turning of the handle and against which the thumb and fingers may exert pressure.

4. A torque handle comprising a body which is symmetrical with respect to an axis of rotation extending longitudinally therethrough, the outer peripheral surface of said body having an undulating groove formed therein extending entirely around said axis of rotation with the peaks of the undulating curve formed by the intersection of the upper edge of the groove with the periphery of the handle and the troughs of the undulating curve formed by the intersection of the lower edge of the groove with the periphery of the handle lying tangent to spaced planes of reference extending through said body in directions perpendicular to said axis of rotation, said groove dividing said body into two sections, each of which, at its respective plane of reference, is substantially elliptical in shape, with the major axis of each ellipse intersecting the major axis of the other ellipse at a right angle, the points of tangency of said peaks and troughs to said planes of reference being spaced around said axis of rotation at intervals of 90°, said groove being of sufficient width and depth to receive the thumb and fingers to provide surfaces against which the thumb and fingers may exert pressure.

5. A torque handle comprising a body which is symmetrical with respect to an axis of rotation extending longitudinally therethrough, the outer peripheral surface of said body having an undulating groove formed therein extending entirely around said axis of rotation with the peaks of the undulating curve formed by the intersection of the upper edge of the groove with the periphery of the handle and the troughs of the undulating curve formed by the intersection of the lower edge of the groove with the periphery of the handle lying tangent to spaced planes of reference extending through said body in directions perpendicular to said axis of rotation, said groove dividing said body into two sections, each of which, at its respective plane of reference, is longer in one dimension than in the other, with the longest dimension of each section intersecting the longest dimension of the other section at a right angle, the points of tangency of said peaks and troughs to said planes of reference being spaced around said axis of rotation at intervals of 90°, said groove being of sufficient width and depth to receive the thumb and fingers to provide surfaces against which the thumb and fingers may exert pressure.
